Primary Examiner — Kelley A Donnelly(74) *Attorney, Agent, or Firm* — Jose Cherson Weissbrot(57) **CLAIM**

The ornamental design for a bedside organizer, as shown and described.

DESCRIPTION

FIG. 1 is a top perspective view of a bedside organizer, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top perspective view of the drawer of the bedside organizer in an opened state; and,

FIG. 10 is a top perspective view of the bedside organizer in a folded state.

The broken lines in the figures are for the purposes of illustrating portions of the bedside organizer, which form no part of the claimed design.

1 Claim, 8 Drawing Sheets(56)
